INVENTOR
FRANCIS HUTTER
BY
D. Anthony Usina
ATTORNEY

UNITED STATES PATENT OFFICE.

FRANCIS HUTTER, OF NEW YORK, N. Y., ASSIGNOR TO THE McCALL COMPANY, OF NEW YORK, N. Y., A CORPORATION OF NEW YORK.

DISPLAY.

Application filed April 17, 1924. Serial No. 707,040.

To all whom it may concern:

Be it known that I, FRANCIS HUTTER, a citizen of the United States, residing in the city, county, and State of New York, have invented certain new and useful Improvements in Display, of which the following is a specification.

The invention relates to improvements in display devices employing partially transparent screens, and aims to provide a simple yet effective device which can be inexpensively manufactured.

An embodiment of the invention is illustrated in the accompanying drawings in which Fig. 1 is a perspective view showing the device in use;

Fig. 2 is a view with the screen removed;

Fig. 3 is an enlarged section on line 3—3 of Fig. 1, illustrating structural features of improvement;

Figs. 4 and 5 illustrate alternative embodiments of the invention.

Transparent devices of various kinds have been heretofore proposed for displaying textile materials and the like but they have frequently been of cumbersome design, employing glass members which are objectionable on account of breakage and difficulty of handling. Prior display devices of which I am aware are usually so constructed that the material displayed must be cut from the piece.

My improved device overcomes these objections and embodies various novel features which will be apparent from the following specification, and pointed out in the appended claims.

The embodiment of the invention illustrated is particularly adapted to show the appearance of a garment made according to a given pattern, of a material displayed in the piece.

Pattern manufacturers make it a practice to print an illustration, (usually on the pattern envelope) to give the purchaser an idea of the appearance of a finished garment made according to the pattern. The patterns are usually identified by number and customers order the patterns by the number.

One object of my invention is to advertise such numbered patterns and to these ends I provide artistically executed screens illustrating garments made according to the patterns. These screens preferably show the

garment on a person and parts of the screen are transparent and other parts are opaque, the transparent parts being provided to show the effectiveness of making up the particular style of garment of a given material on display. Thus the display device serves a double purpose and helps advertise particular patterns and particular materials.

In the drawings 10 represents an easel over which the free end 12 of a bolt of material 14 is draped. The material hangs down loosely behind the back of the easel and the bolt 16 is partly unwrapped and rests in juxtaposition to the easel in full view of the purchasing public.

In front of the part 12 of material on the easel, I place the screen 18 which is preferably made with an opaque background 20 of a neutral tint such as light blue or gray, this background being shown as a black wash in Fig. 1 in the interest of clearness. Part of the screen as indicated at 22 is transparent, and this permits the material draped over the easel to show through. In the drawings, the material is stippled to indicate clearly those parts of the screen which are transparent, and the exposed parts of the bolt of material on display are similarly stippled.

To add to the attractiveness of the display the illustration on the screen includes picture portions which are in suitable opaque colors. The display screen shown in Fig. 1 includes a picture of a girl's head, hands and feet and a picture of a ruching or trimming 30 and also other artistic touches showing the wearer's hat 24 and the collar 25 and cuffs 26 forming part of the garment made according to the pattern illustrated.

The screen is provided with an advertising area 31 in which is printed the name of the pattern manufacturer and also a number to identify the garment pattern corresponding to the style illustrated on the screen.

Garment pattern manufacturers issue many different styles each month and to keep the display screens up to date they must be shipped to the pattern retailers when the different style patterns are issued. It is therefore necessary to provide a screen that can be provided in quantities at a small expense and also one that is of light weight.

to save expense in postage or express charges. Glass screens are impractical as they cannot be printed or otherwise produced cheaply enough for commercial purposes and are difficult to ship without breakage and present various other difficulties of a practical nature.

To overcome the above objections, the screen is preferably formed of celluloid or 10 similar flexible transparent material. This permits pattern manufacturers to have the illustrations printed in quantities by presses. The flexibility of the screen permits it to be 15 rolled and mailed or otherwise shipped in small tubes or packages to dealers without damage.

The screen is preferably provided with reinforcing strips along its top and bottom edges. In Fig. 3 these are illustrated at 20 32 and 33 as U-shaped sheet metal strips which are frictionally secured to the screen by pressing the strips in a suitable die or other tool.

To the upper strip 32, slips 34—34 are 25 secured which serve to suspend the screen and also to frictionally hold the material on the easel. As shown in Fig. 3, the clip 34 has a shank 36 which is secured between a wall of the U-shaped strip and the upper 30 part of the screen. The clip has a rebent portion 38 and a hooked end 39 adapted to be yieldingly pressed over the material where it is folded over the top of the easel. Thus the clips serve the double function of 35 suspending the screen and clamping the fabric displayed to the easel.

The easel 10 is of light, yet rigid, construction being formed of light sheet metal with rolled top and side edges as at 40 and 40 42 and provided with a marginal stiffening rod 44. The lower edge of the easel is rebent to form a flange 46 which provides a U-shaped pocket along the lower edge. This pocket receives the lower loose end of the 45 material displayed and also the lower end of the screen and prevents both from becoming dislodged. For supporting the easel in an inclined position, a back rest or leg 48 is pivoted to suitable brackets 50 which are 50 spot-welded or otherwise secured to the back of the device as shown.

In Figs. 4 and 5 I have illustrated slightly modified embodiments of the invention, in which the material is displayed through 55 at least two picture portions of the screen. In Fig. 4, the screen 18^a is formed with two transparent portions 22^a and 22^b. The transparent portion 22^a permits the showing through of the material 12^a on that part of the screen which illustrates a three-quarter 60 front view of a person wearing a garment made according to the particular pattern illustrated. The transparent portion 22^b is placed on a picture portion 50 of the screen 65 which represents a mirror. The screen is so

designed that the same illustrates a three-quarter back view of the garment shown by the main picture. In other words, two views of a garment made according to the particular pattern advertised are illustrated on this screen, and the material shows through the screen in both views. In the drawing the material is illustrated by the shading which is in the form of fine stippling to show a checked broadcloth. In this screen the background instead of being a plain wash as shown in Fig. 1, shows the wall 52 and floor 54 of a room, this adding to the attractiveness of the display screen.

In Fig. 5 I have shown a screen of different design in which the transparent portion 22^c of the style picture is substantially the same as that shown in the other figures and the material 12^a shows therethrough in practically the same manner. In this figure I have shown a transparent portion 22^c to permit the material to be displayed to show through as at 12^a, the effect being to depict a piece of material draped over a chair 54. Certain opaque shade lines 56 are printed on the screen to simulate folds or surface irregularities of a piece of draped material. In this figure the background 52^a and foreground or floor 54 are definitely delineated and a piece of furniture 58 is shown in the foreground to add to the attractiveness of the display.

Though I have described with great particularity the construction and arrangement of the particular embodiment of the invention illustrated, it is not to be construed that I am limited thereto as changes in the arrangement and substitution of equivalents may be made by skilled artisans without departing from the invention as defined in the appended claims.

What I claim is:—

1. A display device for illustrating the appearance of a garment made according to a given pattern of a material displayed in the piece comprising an easel over which one end of the piece of material displayed is draped, and a flexible screen supported on said easel having an opaque background, transparent portions and picture portions, and an advertising area bearing the name of the pattern manufacturer and an identifying number corresponding to the garment pattern illustrated on said screen and means for engaging the opposite ends of said flexible screen to hold it flat against the material draped over the easel.

2. A display device comprising an easel for supporting an end of a bolt of goods displayed in the piece, a flexible screen hung on said easel in front of the material thereon, said screen having an opaque background, transparent portions and picture portions designed to illustrate the appearance of a garment made of the ma-

terial displayed according to a given pattern, said screen having marked thereon characters to identify the pattern illustrated and means for holding the flexible screen flat.

3. A display device comprising an easel for supporting an end of a bolt of goods displayed in the piece, a flexible celluloid screen having a protective strip secured 10 along the top edge thereof and means engaging said strip whereby the screen can be detachably secured to the easel, said screen having transparent portions, opaque portions, and picture portions to illustrate 15 the appearance of a garment made of the material displayed.

4. A display device comprising a sheet metal easel having reinforced marginal edges and having an upturned integral marginal flange along its lower edge forming a U-shaped pocket, said easel being adapted 20 to support a piece of textile material with the lower end in said U-shaped pocket, a screen having transparent and opaque 25 portions adapted to illustrate a pattern and clips on said screen adapted to support it and to frictionally hold the piece of material in proper position on the easel.

5. A display device comprising in combination, an easel adapted to have a piece 30 of dress material draped over it, a partially transparent flexible screen illustrative of garment patterns, and a single means for

supporting the screen and clamping the material to said easel.

6. In combination a display device including a support for a piece of material, a partly transparent and partly opaque screen adapted to be hung in front of the material on said support and supporting 40 clips fixedly secured to said screen for clamping the material in place on said support.

7. In combination a display device including an inclined flat supporting member arranged to have an end of a bolt of material draped thereover, a partly transparent and partly opaque flexible screen detachably secured to said support in front 45 of the material draped over the same and means formed on the supporting member for preventing dislodgment of the lower end of the screen and the material displayed.

8. A display device comprising in combination an easel for supporting a piece of 50 material to be displayed and a partially transparent flexible screen illustrative of garment patterns.

9. A screen adapted for use as a display device comprising a partially transparent 55 flexible sheet adapted to be rolled into a small package to facilitate the shipment thereof.

In witness whereof, I have hereunto signed my name.

FRANCIS HUTTER.
